UNITED STATES PATENT OFFICE.

FREDERICK H. LOCKWOOD, OF ALAMEDA, CALIFORNIA.

COMBINATION CHAMFER AND BUTT GAGE.

No. 806,417.

Specification of Letters Patent.

Patented Dec. 5, 1905.

Application filed August 21, 1905. Serial No. 275,037.

To all whom it may concern:

Be it known that I, FREDERICK H. LOCKWOOD, a citizen of the United States, residing at Alameda, in the county of Alameda and State of California, have invented new and useful Improvements in Combination Chamfer and Butt Gages, of which the following is a specification.

My invention relates to an improved carpenter's gage, and especially to a combined butt and chamfer gage.

In gaging or marking the butting faces of door-jams and doors where the butt-hinges are to go it has often heretofore been a matter of difficulty to work in the narrow angles allotted by the door-jamb and wall construction. It is essential to the true hanging of the door that the butt-gaging be done from the front or the side toward which the door opens. If it is attempted to gage the butt-cuts from the wooden stop on the jamb and against which the door closes, the door is liable to be hung crooked, especially where there are a number of similar doors in a building to be hung, by reason that the doors will all vary more or less in thickness. Also it is a matter of inconvenience and loss of time in carpentry with the usual single-point gages in marking the corners for future chamfering of square posts, pillars, and the like.

The object of my invention, then, is to provide a gage which can be used for gaging butts from the inside of the door no matter how confined or cramped the space or what ledges may interfere, which will gage and mark both the width and thickness of the cut at one operation, and which will gage and mark both sides of a post or the like for chamfering; and, moreover, it is my object to make such a tool which shall be neat, durable, practical, and compact and which may be carried easily in the pocket.

It is also my object to provide a gage for making two parallel marks on the same flat surface at one operation.

The invention consists of the parts and the construction and the combination of parts, as hereinafter more fully described and claimed, having reference to the accompanying drawings, in which—

Figure 1 is a side view of my gage. Fig. 2 is a plan view of Fig. 1. Fig. 3 is an end view looking from the right of Fig. 1.

A represents the stock or body of my device made of suitable material, as metal, and of any appropriate or desired size or design.

The drawings represent a practical full-size device. This stock has a longitudinal groove or slot 2 along its bottom. The opposite walls are concaved to form a guideway and 60 housing for a gage-beam or sliding piece 3 carrying the marker 4 at one end. This sliding piece has a vertical groove or concavity in its end, and the marker has a corresponding convexity, so that a single screw serves to 65 hold the marker removably to the piece 3 and at the same time the marker is prevented from turning. The marker is slotted so that as it becomes worn or dull it may be dropped down or removed and sharpened or provision 70 made for a deeper or shallower mark or cut, the groove 2 being deep enough to accommodate the end of the marker, which may project above the sliding piece. The stock is perforated at right angles to groove 2 to receive a second beam or sliding piece 5, which carries a similar marker 6 at its marking end, secured in the same way as marker 4. If desired, the sliding piece 5 may be graduated as shown at 7 and the bottom of the stock A from 75 80 the piece 5 may be graduated as shown at 8. In order to adapt the gage to mark two parallel lines on the same plane surface, as it is sometimes desired to do in carpentry, I may provide a second sliding piece 5', arranged 85 parallel with the sliding piece 5 and locked in any desired position by a set-screw 10'. The sliding piece 5', like the piece 5, is made round and carries a removable adjustable marker 6'. If desired, the piece 5' may be graduated, as 90 shown at 7'. By turning the pieces 5 5' in the position shown in dotted lines, Fig. 1, they may be used conjunctively to draw two parallel lines on the same flat surface, or either one of the pieces 5 or 5' may be used in conjunction with the piece 3 where it is desirable to mark two sides of any rectangular object, as in marking corner-posts for chamfering. Only one of the pieces 5 or 5' will be used at the same time with the piece 3, that piece 5 or 5' 95 which is not in use being temporarily removed, if necessary, by having the marker members 6 constructed in the fashion shown and arranged directly on the ends of the sliding pieces.

The device is capable of being worked in very shallow angles.

It is possible that various modifications in my invention may be made without departing from the principle thereof, and I do not wish 110 to be understood as limiting myself to the specific construction shown and described.

Having thus described my invention, what I claim, and desire to secure by Letters Patent, is—

1. A combination chamfer and butt gage comprising a body portion having two gage-beams arranged at right angles to each other and slidably mounted in the body, said gage-beams having adjustable removable markers at their extremities, one of said beams having a recessed end and one of said markers being seated in the recess of said beam, and means securing said marker in its recessed seat.
2. A gage comprising a block having a longitudinal channel along one side, a sliding piece housed in said channel the end of said piece being concaved in the plane of the channel, and a longitudinally-slotted marker having a convexity fitting the concavity in the end of the sliding piece, and a screw fitting the slot in said marker and perforation in the end of the sliding piece.
3. A gage comprising a body portion and an adjustable sliding piece carried thereby,

said sliding piece having its end transversely concaved, and a slotted marker provided with a corresponding convexity to fit said concavity and lock the screw to hold the marker to the sliding piece.

4. A gage comprising a body, two sliding pieces carried thereby and adjustable and turnable therein and parallel with each other, and a third marking-piece carried by the body and arranged at right angles to the first-named sliding piece, and markers carried by said sliding pieces, said third marking-piece having a recessed seat in its end and one of said markers being slidably and non-turnably seated thereon, and means securing the last-named marker in position.

In testimony whereof I have hereunto set my hand in presence of two subscribing witnesses.

FREDERICK H. LOCKWOOD.
